UNITED STATES PATENT OFFICE.

GILBERT L. CROWELL, JR., OF ARLINGTON, NEW JERSEY.

DESIGN FOR A HANDLE FOR SPOONS OR SIMILAR ARTICLES.

SPECIFICATION forming part of Design No. 33,323, dated October 9, 1900.

Application filed September 17, 1900. Serial No. 30,364. Term of patent 7 years.

To all whom it may concern:

Be it known that I, GILBERT L. CROWELL, Jr., a citizen of the United States, residing at Arlington, in the county of Hudson and State of New Jersey, have invented a new and original Design for Handles for Spoons, Forks, and Similar Articles, of which the following is a description, reference being had to the accompanying drawings, which illustrate the design.

Figure 1 is a plan or elevation view of the front or obverse side of a spoon, the handle of which embodies my design, the dotted lines showing how the handle may be applied to a fork. Fig. 2 is a similar view of the reverse or rear side of the spoon and handle. Fig. 3 is a cross-section on the plane *a a* of Fig. 1.

The general outline of the handle is of the spatulate order. Along and immediately adjacent to the opposite edges of both sides of the handle and substantially parallel with such edges are the lines of fluting or beading *A A*, which terminate in scroll-like ornamentations *B B*, which form the outline of part of the head of the handle and are substantially the same on both its sides. Between the scroll-like ornamentations at the head of the flutings is placed, on both sides of the handle, a conventionalized shell figure *C*, at the base of which is located a series of rounded flutings *D*, which constitute the remainder of

the outline of the head of the handle. At the heel of the shank of the handle, on the under side of the same, is a shell figure *E*, substantially the same as the shell figure *D* on the under side of the head of the handle. At a point near the juncture of the handle with the bowl the sides of the handle converge slightly, as shown at *F*, thus giving that portion of the handle slightly greater width than that immediately adjoining it toward the head of the handle. The lines of fluting follow the contour of the sides of the handle. The surfaces of the handle, between the lines of fluting on both sides thereof, are preferably without ornamentation.

The essential feature of this design consists of a handle for a spoon, fork, or similar article having a spatulate outline or form and lines of fluting or beading extending along the opposite edges on both sides of the handle and terminating at its head in scroll ornamentation, substantially as described.

What is claimed as new is—

The design for the handle of a spoon, fork or other similar article, substantially as shown and described.

GILBERT L. CROWELL, JR. [L. S.]
